Primary Examiner — Christy Nemeth*Assistant Examiner* — Justin M. Donaldson(74) *Attorney, Agent, or Firm* — William Gray Mitchell(57) **CLAIM**

The ornamental design for a T-shaped junction box, as shown.

DESCRIPTION

FIG. 1 is a front, top perspective view of the design; FIG. 2 is a back, bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a back view thereof.

1 Claim, 8 Drawing Sheets(56)
